UNITED STATES PATENT OFFICE.

ANDREW FORREST, OF CHICAGO, ILLINOIS, ASSIGNOR TO INTERSTATE IRON AND STEEL COMPANY, OF CHICAGO, ILLINOIS, A CORPORATION OF ILLINOIS.

INGOT-CASTING APPARATUS.

Application filed July 31, 1925. Serial No. 47,208.

My invention relates especially to molds and stools for casting ingots from molten metal, and its object is to provide a device in which the metal after cooling does not stick in the lower opening of the mold chamber and the ingot can be lifted out of the mold without pushing on the bottom of the ingot.

In casting ingots it is customary to use molds of either the so-called big-end-up type in which the necked-in or reduced part of the mold chamber is at the bottom of the mold, or the so-called big-end-down type in which the contracted part of the mold chamber is at the top. In both types the metal is liable to leak out and when cooled stick in the lower opening of the mold chamber, so that frequently it is impossible to lift the ingots out of the former type of molds and to pull the latter type of molds off the ingots without consuming extra time and employing further labor to loosen or remove the metal thus adhering to the mold, during which operation the mold is out of commission for further casting operations, and sometimes is unsuitable for further use. In some cases as many as seven molds in a bank of twenty have thus been rendered at least temporarily useless. In some respects the big-end-up type is preferable to the other type, because in the stripping operation the cooled ingot can be removed from this type of mold without removing the mold itself from its casting position in the pit, whereas with the other type after the mold is lifted or stripped off the ingot it must be deposited elsewhere until the ingot is removed and must then be returned to casting position in the pit. However, in the use of big-end-up molds it has heretofore been customary to provide the reduced or necked-in lower end of the mold chamber with an interior closure plate having an arm or plug projecting through the opening so that force can be applied to the plug to cause the plate to push on the bottom of the ingot to aid in lifting the latter out of the mold. This practice is objectionable for several reasons and does not obviate the sticking of the metal in the lower opening of the chamber as the metal leaks past the plate and sticks in the mold opening.

My invention obviates this liability of the metal to stick in the lower opening of the mold chamber and permits the ingot to be

lifted out of the big-end-up mold without pushing on its bottom, and not only effects a great saving of time and labor in the stripping operation itself, but also reduces the number of expensive molds required as it ensures the uninterrupted use of the full quota of mold equipment.

In the accompanying drawings, which illustrate a practical embodiment of my invention and in which the same reference numerals indicate the same or similar parts in the different views, Fig. 1 is a view partly in longitudinal section and partly in side elevation showing a big-end-up mold and an associated stool constructed in accordance with my invention; Fig. 2 is a bottom plan view of the same mold looking into its chamber and showing the shape of its bottom end, and Fig. 3 is a top plan view of the stool showing the shape of its different parts.

In carrying out my invention I preferably employ the big-end-up type of the mold, as indicated generally by the reference numeral 1, which may be of any suitable size and contour of chamber, and provide a stool indicated generally by the reference numeral 2 which forms the bottom of the mold during the casting of the ingot, these parts being suitably constructed to seal the lower end of the mold chamber when assembled to prevent the metal from leaking out, and to permit the mold to be readily and easily seated on the stool. In the embodiment here shown, the lower end of the mold is provided with a bell-mouth formed by an outwardly beveled or flared cylindrical lip 3 and having an inner annular flat seat 4 surrounding the corresponding end of its chamber, and the top of the stool is provided with a conical frustum spigot 5 constructed to pass into the bell-mouth of the mold and having a flat upper seat 6 to register with and support the seat 4 of the mold. In practice the only bearing of the mold on the stool is upon the seat 6 at the inner end of the spigot in order that the entire weight of the mold on the stool may be confined and concentrated to the relatively small area of the surfaces 4 and 6 transverse to the axial line of the mold, and thereby make a tight joint to seal the bottom end of the mold and prevent the molten metal from leaking out. For this purpose suitable clearance is provided between all other opposite surfaces of the mold and stool. Thus, for example,

the height of the spigot is slightly greater than the depth of the mouth to provide clearance between the lower edge of the mold and the body of the stool; in practice a separation of about one-sixteenth ($\frac{1}{16}$) of an inch between these surfaces provides sufficient clearance without permitting the mold to rock on the stool. Also, for the same primary purpose, the increasing diameter of the bell-mouth is slightly greater than that of the spigot to provide clearance between their sides, in practice a clearance of about one-eighth ($\frac{1}{8}$) of an inch at this location being sufficient; and this feature is of further advantage because in assembling the parts the mold slips easily on the stool without preliminary axial alinement. These clearances also enable the parts to make an easy fit or assembly. Furthermore, the bell-mouth and spigot preferably are conical so that the mold seats on the stool in any of its rotary positions; the recess in the mold seats on the spigot on the stool in any rotary relation of these parts, thereby obviating the necessity of axially turning the mold to any particular or predetermined position above the stool in order to properly assemble it on the latter.

The stool is of cast metal, and its face within the mold-chamber can be of any shape to provide the desired contour of the end of the ingot; and the lower surface of the stool may be plain or provided with a base 7 as desired.

When a mold is seated on the stool, as shown for example in Fig. 1, the lower end of the mold rests only on the transverse seat 6 and the joint is sealed by the surfaces 4 and 6. When the molten metal is poured into the mold it does not leak out of the chamber, and the ingot does not stick in the lower opening of the mold. When the stool is used with either parallel-walled or big-end-down molds the latter may be stripped off the ingot by pulling it off in the

ordinary manner; when a big-end-up mold is used with the stool the ingot may be lifted out of the mold without pushing on the bottom of the ingot; in any case there is no leakage and no necessity of preliminarily loosening or removing any adhering metal. The stripping operation in any type of mold is thus simplified and rendered uniform, all the molds remain in service for successive castings, and saving in time and equipment is obtained. Also, as the greatest wear on the walls of the mold chamber occurs at the bottom, particularly in all molds having either integral or necked-in bottoms, my invention effects a saving in expense of equipment as the separate stools can be replaced at greatly reduced cost in comparison with the cost of renewing or replacing the molds, and the same stools can be used with different forms or types of molds.

I claim:

1. An ingot casting apparatus comprising a mold and a stool having a cylindrical bell and spigot seating joint.

2. An ingot casting apparatus comprising a mold having a bell-mouth at its lower end, and a stool having a conical spigot to enter the mouth when the mold is assembled on the stool, the stool and mold having opposite annular seating faces disposed in a plane transverse to the axial line of the mold.

3. In an ingot casting apparatus, a big-end-up mold having a bell-mouth at its lower end formed with an annular seat transverse to the axial line of the mold and an outer flared cylindrical lip, and a stool having a conical spigot formed with an annular seat to co-operate with the mold-seat to seal the mold, the lip and spigot being formed to provide clearance between their sides and between the lower edge of the lip and the body of the stool.

In testimony whereof I hereto affix my signature.

ANDREW FORREST.
